UNITED STATES PATENT OFFICE.

WILLIAM F. DAVITT, OF MANCHESTER, NEW HAMPSHIRE.

PICKER STICK.

1,406,544.

Specification of Letters Patent. Patented Feb. 14, 1922.

Application filed September 21, 1921. Serial No. 502,207.

To all whom it may concern:

Be it known that I, WILLIAM F. DAVITT, a citizen of the United States, and a resident of Manchester, in the county of Hillsbor-

5 ough and State of New Hampshire, have invented certain new and useful Improvements in Picker Sticks, of which the following is a specification.

The present invention relates to a picker 10 stick mechanism or motion for looms, and has for its object to provide a device of this character which eliminates all straps, except the lug strap, which operates in such a manner as to throw the shuttle straight 15 across the loom on the race board, which precludes all possibility of the picker stick jumping out of its holder with resulting damage to the cloth or shuttle, or both, and which is in general of simple and durable 20 construction, reliable in operation and easy and inexpensive to manufacture.

Other objects and advantages of the invention reside in certain novel features of construction, combination and arrangement 25 of parts which will be hereinafter more fully described and particularly pointed out in the appended claims, reference being had to the accompanying drawings forming part of this specification, and in which:

30 Figure 1 is a side elevational view, illustrating the preferred embodiment of the invention;

Figure 2 is a group view in perspective, showing the elements of the invention im- 35 mediately prior to assembly; and

Figure 3 is a view in horizontal section on line 3—3 of Figure 1.

Referring to the drawings wherein for the sake of illustration is shown the preferred embodiment of the invention, the numeral 10 designates the loom side upon which a support, designated generally at 11 is arranged. The support 11 includes a body portion 12 and a pair of spaced parallel 45 arms 13 constituting a yoke. A picker stick designated at 15 has its lower end disposed between the arms 13. At the lower end of the picker stick 15 a shoe 16 is arranged, and the shoe and the picker stick are provided 50 with complementary notches, designated at 15^a and 16^a respectively which in assembly define a pivot bearing in which a pivot bolt 17 is operatively arranged, the pivot bolt being carried by the arms 13 of the yoke 55 whereby the picker stick is pivotally mounted on the support. A toe 18 extends later-

ally from the shoe 16 over the body portion of the support and is engageable with the support to limit the movement of the picker stick.

The body portion 12 of the support is cut away at one side thereof to provide a recess 12^a and in this recess a frame 20 is arranged. Offset bearing lugs 21 and 22 are integrally formed with the frame 20 or otherwise secured thereto and in assembly these bearing lugs are disposed beneath the body portion 12. Means is provided for securing the frame 20 to the body portion 12 and preferably consists of bolts 23 and 24 extending 60 through suitable bolt holes provided therefor in the frame 20 and the body portion 12 and secured in position by means of nuts 25 and 26 threaded on the bolt. A sliding shaft 27 is journaled in the bearing lugs 65 21 and 22 and has fixed thereto at one end a slotted head 28. A connecting bar 29 operates in the slot of the head 28 and is provided with stop lugs 30 and 31 cooperable with the head 28. Common means is provided for securing the shoe 16 and the connecting bar 29 to the picker stick and preferably consists of a single bolt 32 extending 70 through suitable bolt holes provided therefor in the shoe 16, the picker stick 15 and 75 the connecting bar 29, and secured in position by means of a nut 33 threaded on the end thereof.

A compression coil spring 35 encircles the sliding shaft 27 between the bearing 80 lugs 21 and 22 and abuts the bearing lug 22 at one end, the other end of the coil spring engaging a collar 36 adjustably fixed on the sliding shaft 27 by means of a set screw 37.

In operation, when operative movement 85 is imparted to the picker stick 15, the sliding shaft 27 also moves by virtue of the connection between the picker stick and the sliding shaft afforded by the connecting bar 29 and the slotted head 28. This movement 90 of the sliding shaft 27 is resiliently resisted by the coil spring 35, as this movement further compresses the coil spring. The spring 35 thus functions to cushion the movement 95 of the picker stick, thereby preventing it 100 from striking the wall of the slot in the shuttle box. The resistance offered by the spring 35 to the movement of the sliding shaft may be readily varied by adjusting the collar 36 on the sliding shaft 27.

110 By providing this picker stick motion or mechanism the necessity for using straps

to check or control the picker stick in its movements is avoided. It is well known in the art that such straps stretch and result in throwing the shuttle from near the top 5 of the picker stick in an elliptical path, the curve of which increases as the strap stretches. In the mechanism of the present invention the shuttle is thrown in a straight path across the loom on the race board. 10 Moreover, when the straps heretofore used broke, the picker stick jumped out of the holder thereby working damage to the cloth or shuttle or both. In the present invention it is impossible for the picker stick to so 15 jump and work injury to these elements.

I claim:

1. A picker stick mechanism comprising a support including a body portion and a yoke having a pair of arms, a picker stick 20 having its lower end disposed between said pair of arms, a shoe associated with said picker stick and having a toe extending therefrom and engageable with the body portion to limit the movement of the picker stick, said picker stick and said shoe having complementary notches defining a pivot bearing, a pivot bolt carried by said pair of arms and operating in said pivot bearing whereby said picker stick is pivotally mounted on said support, said body portion having a recess at one side, a frame disposed in said recess, offset bearing lugs carried by said frame and disposed beneath said body portion, means 30 for securing said frame to said body portion, a sliding shaft journaled in said bearing lugs, a slotted head connected with said sliding shaft, a connecting bar operating in said slotted head and secured to said picker stick, a coil spring arranged on said shaft and engaging one of said bearing lugs 35 at one end and a collar adjustably fixed to said shaft and engaging the other end of said coil spring.

bar operating in said slotted head and having stop lugs cooperable therewith, common 40 means for securing said shoe and said connecting bar to said picker stick, a coil spring arranged on said shaft and engaging one of said bearing lugs at one end, and a collar fixed to said shaft and engaging the 45 other end of said coil spring.

2. A picker stick mechanism comprising a support including a body portion and a yoke having a pair of arms, a picker stick 50 having its lower end disposed between said pair of arms and pivotally secured thereto, a frame secured to said body portion, offset bearing lugs carried by said frame and disposed beneath said body portion, a sliding shaft journaled in said bearing lugs, a slotted head connected with one end of said sliding shaft, a connecting bar operating in said slotted head and secured to said picker stick, a coil spring arranged on said shaft and engaging one of said bearing lugs 55 at one end and a collar adjustably fixed to said shaft and engaging the other end of said coil spring.

3. A picker stick mechanism comprising a support, a picker stick pivotally mounted 60 on said support, a frame secured to said support, bearing lugs carried by said frame, a sliding shaft journaled in said bearing lugs, a connecting bar secured to said picker stick and operatively connected with said 65 sliding shaft, a coil spring arranged on said shaft and engaging one of said bearing lugs at one end, and a collar adjustably fixed to said shaft and engaging the other 70 end of said coil spring.

WILLIAM F. DAVITT.
